UNITED STATES PATENT OFFICE.

ELMER H. DARSIE, OF DONORA, PENNSYLVANIA.

COMBINATION-MEASURE.

SPECIFICATION forming part of Letters Patent No. 735,951, dated August 11, 1903.

Application filed September 30, 1902. Serial No. 125,351. (No model.)

To all whom it may concern:

Be it known that I, ELMER H. DARSIE, a resident of Donora, in the county of Washington and State of Pennsylvania, have invented a new and useful Improvement in Combination-Measures; and I do hereby declare the following to be a full, clear, and exact description thereof.

My invention relates to combination-measures, and has special reference to dry measures for grain, vegetables, produce, fruit, nails, and many other like dry articles, &c.

The object of my invention is to provide a cheap, simple, and effective combination-measure for holding and measuring different things and articles which can always be maintained in position when the parts are together, as well as one in which parts or sections of the same can be removed and used, leaving the other parts in position to be also used as desired.

My invention consists, generally stated, in the novel arrangement, construction, and combination of parts, as hereinafter more specifically set forth and described, and particularly pointed out in the claims.

To enable others skilled in the art to which my invention appertains to construct and use my improved combination-measure, I will describe the same more fully, referring to the accompanying drawings, in which—

Figure 1 shows my improved combination-measure, one half being shown in full lines and the other half being shown in section. Fig. 2 is an enlarged top view of the same. Fig. 3 is an enlarged detail section of the joint for the different members or sections composing the measure. Fig. 4 is a detail sectional view showing one of the members or sections removed and having a removable bottom inserted therein. Fig. 5 is a top view of such bottom, showing the same in position in the member or section; and Figs. 6 and 7 are top views of other forms of the measure.

Like symbols of reference herein indicate like parts in each of the figures of the drawings.

My improved combination-measure is shown at A, and the same is composed of different-size members or sections a, b, c, and d, which are preferably made from galvanized sheet-metal plates and bent to shape to form

each section in the form of a frustum of a cone. The side edges of each section are secured together in any suitable manner, and the bottom of each cone-shaped section is in the smaller end 1 thereof, while the top is at the larger end 2 thereof. The sections a, b, c, and d are telescopically connected together by securing in any suitable manner to the interior surface 3' of the tapered sides 3 of the upper section a and middle sections b, c, and d, adjacent to the bottom 1 thereof, the annular ring 4 and securing in any suitable manner to the exterior surface 3" of the tapered sides 3 of the middle sections b, c and lower section d and adjacent to the top 2 thereof the annular ring 5, the bottom edge 5' of which is adapted to rest on the top edge 4' of the ring 4 when the sections a, b, c, and d are in position to form the measure. The lower section d is provided with a bottom or base 6, which is secured thereto in any suitable manner and adjacent to the bottom 1 thereof, and a ring or collar 7 is secured in any suitable manner to the exterior surface 3" of the tapered sides 3 of the top 2 of the upper section a, while handles 8 are pivoted or secured to the exterior surface 3" of said tapered sides 3 of the upper section a and opposite each other for the purpose of lifting said measure A or the section a when removed therefrom.

When it is desired to use my improved combination-measure, all that is necessary is to assemble the different sections a, b, c, d together or in place to form the measure A, which can be accomplished by inserting the base 6 of the lower section d into the large end 2 of the middle section c and allowing said lower section d to be dropped down through said middle section c, so that the lower edge 5' of the ring 5 at the top 2 of the lower section d will come in contact with the upper edge 4' of the ring 4 at the bottom 1 of the middle section c, while the side face 5" of the ring 5 on said lower section d will be wedged or forced against the interior surface 3' on the tapered sides 3 of the middle section c and the side face 4" of the ring 4 on the middle section c will be wedged or forced against the exterior surface 3" on the tapered sides 3 of the lower section d. The middle section c, carrying the lower section d, is then dropped into and

through the other middle section *b* in like manner, so that the lower edge 5' of the ring 5 on said middle section *c* will come in contact with the upper edge 4' of the ring 4 on the 5 middle section *b* and the side face 5" on said ring 5 will be wedged or forced against the interior surface 3' on the tapered sides 3 of the middle section *b* and the side face 4" on said ring 4 will be wedged or forced against 10 the exterior surface 3" on the tapered sides 3 of said middle section *c*. After this is done the middle section *b*, carrying the other middle section *c* and lower section *d*, is then dropped into and through the upper section 15 *a* in like manner, so that the lower edge 5' on the ring 5 of said middle section *b* will come in contact with the upper edge 4' of the ring 4 of the upper section *a* and the side face 5" of said ring 5 will be wedged or forced against 20 the interior surface 3' on the tapered sides 3 of the upper section *a* and the side face 4" on said ring 4 will be wedged or forced against the exterior surface 3" on the tapered sides 3 of said middle section *b*. The measure A 25 is now ready for use in holding different ingredients, articles, &c., and such measure is so arranged or constructed as to size that the members or sections *a*, *b*, *c*, and *d* in position will hold a predetermined quantity—as, for 30 instance, a one-half bushel—while the members or sections *b*, *c*, and *d* in position will hold a peck, the members or sections *c* and *d* in position holding a one-half peck and the member or section *d* holding one-quarter peck, 35 so that the holding amount of the measure is always known, and in case of the removal of one or more of said sections or members the holding amount of such member or members or the remaining member or members in position is likewise always known.

When it is desired to remove the upper member or section *a* from the measure, all that is necessary is to force down said section by any suitable means or manner, so 45 that the rings 4 and 5 on the sections *a* and *b*, respectively, are free from each other and the tapered sides 3 of the sections *b* and *c*, respectively, which will allow said section *a* to be free from contact with the section *b* and permit the same to be dropped, so that the 50 remaining sections *b*, *c*, and *d* in position can be lifted and the section *a* removed from around the other sections *b*, *c*, and *d*. Each of the other sections *b* and *c*, or both, can be 55 removed separately from each other or together from the lower section *d* in like manner, or all three sections *a*, *b*, and *c* can be removed together from the section *d*, as above described.

60 In case it is desired to use any one of the members or sections *a*, *b*, *c* for the storing of materials, ingredients, &c., each of such sections can be used separately or together, as shown in Figs. 4 and 5, wherein the member 65 or section *a* has applied thereto the removable bottom 9, which can be dropped or inserted into the section *a* through the top 2

thereof and the outer circular edge of such bottom 9 rest upon the top edge of the ring 4 on the bottom 1 of said section *a*. The bottom 9 is provided with angular pieces 10, secured to the under face 9' of said bottom 9 in any suitable manner, as by the rivet 9", so that the projecting portion 10' on said angular pieces 10 will engage with the inner face 75 4" of said ring 4 and act to wedge or hold said bottom 9 in place.

It will be obvious that the different members or sections of my improved combination-measure can be made square, as shown in 80 Fig. 6, oval, as shown in Fig. 7, or such other form desired and that such measure can be made to hold different capacities than those described. These and various other modifications and changes may be made without 85 departing from the spirit of the invention or sacrificing any of its advantages.

It will thus be seen that by my improved measure there is a series of graduated measures which can be used for the storing of materials, articles, ingredients, &c., presents a dry measure which is practically air-tight around the connecting-joints of the sections and bottom employed, so as to prevent the dropping of the contents contained within 95 the sections or section through said joints or joint. It will also be seen that the measure is capable of varied and wide uses and that the simple clamping or wedging device for holding the sections and bottom in place will 100 prevent displacement of the parts when in use and render the same a simple and useful article.

What I claim as my invention, and desire to secure by Letters Patent, is—

1. A graduated measure, composed of a plurality of graduated cone-shaped members or sections, the lower one of which is provided with a bottom or base, said sections being telescopically connected together by a ring on 110 one section fitting under a ring on the other connecting-section, and such rings being adapted to be wedged or forced against the tapered sides of such connecting-sections.

2. A graduated measure, composed of a plurality of graduated cone-shaped members or sections, the lower one of which is provided with a bottom or base, said sections being telescopically connected together by a ring secured on one section fitting under a ring secured on the other connecting-section, and such rings being adapted to be wedged or forced against the tapering sides of such connecting-sections.

3. A graduated measure, composed of a plurality of cone-shaped members or sections, the lower one of which is provided with a bottom or base, said sections being telescopically connected together by a ring secured on the upper section fitting under a ring secured on the next connecting-section, and such rings being adapted to be wedged or forced against the tapered sides of said upper section and its connecting-section.

4. A graduated measure, composed of a plurality of graduated cone-shaped members or sections, the lower one of which is provided with a bottom or base, said sections being telescopically connected together by a ring secured at the bottom of the upper section fitting under a ring secured at the top of the next connecting-section, and such rings being adapted to be wedged or forced against the 10 tapered sides of said upper section and its connecting-section.

5. A cone-shaped measure having a ring secured at its base, a removable bottom plate adapted to rest on said ring, and means on 15 said bottom plate for forming a wedging engagement with said ring to hold said plate in place.

6. A cone-shaped measure having a ring secured at its base, a removable bottom plate 20 adapted to rest on said ring, and projections on said bottom plate for forming a wedging

engagement with said ring to hold said plate in place.

7. A cone-shaped measure having a ring secured at its base, a removable bottom plate 25 adapted to rest on said ring, and angular projections secured to said bottom plate for forming a wedging engagement with said ring to hold said plate in place.

8. A cone-shaped measure having a ring secured at its bottom, a removable bottom adapted to rest on said ring, and angular projections on the under face of said bottom adapted to be wedged against said ring for holding 30 said bottom in place.

In testimony whereof I, the said ELMER H. DARSIE, have hereunto set my hand.

ELMER H. DARSIE.
